POLISHING DEVICE

Sergio Bayan, Lucena Tayabas,
Philippine Islands

Application December 7, 1932. Serial No. 646,174

6 Claims. (Cl. 91—39)

This invention relates to polishing devices, especially adapted for treating and polishing floors and the like, and has for the primary object, the provision of a device of the above stated character which may be conveniently manipulated to apply a polish to a floor and thoroughly rub the latter to provide a highly polished and protective finish to the floor and is so constructed as to accommodate a fibrous medium, preferably a cocoanut covering to act on the floor after and during the application of the polish to the floor.

With these and other objects in view this invention consists in certain novel features of construction, combination and arrangement of parts 15 to be hereinafter more fully described and claimed.

For a complete understanding of my invention, reference is to be had to the following description and accompanying drawings, in which

Figure 1 is a side elevation illustrating a polishing device constructed in accordance with my invention.

Figure 2 is a top plan view partly in section illustrating the same.

Figure 3 is a vertical sectional view illustrating the device.

Figure 4 is a sectional view taken on the line 4—4 of Figure 3.

Figure 5 is a fragmentary elevation illustrating the attachment of the operating handle to the device.

Figure 6 is a sectional view taken on the line 6—6 of Figure 3.

Figure 7 is a plan view partly in section of a handle attaching bracket.

Figure 8 is a side elevation illustrating the bracket.

Referring in detail to the drawings, the numeral 1 indicates a holder including inner and outer holding elements 2 and 3, relatively spaced to clamp therebetween a portion of a cocoanut shell 4 and its fibrous pod 5 after the usual cocoanut meat has been removed, the pod projecting slightly beyond the shell to form a fibrous

brush-like portion 6. The outer element 3 is of cup-shape to engage a portion of the outer surface of the pod with the latter projecting outwardly therefrom. The inner element 2 is of solid formation and is of semi-spherical shape

for the purpose of forming a weight. The inner and outer elements 2 and 3 are provided with alining openings to permit a sleeve 7 to extend therethrough. An attaching plate 8 is apertured to receive the sleeve 7 and rests against the outer element 3 and is equipped with pins 9 to embed

into the pod of the cocoanut shell. Arcuate ears 10 project from opposite edges of the plate 8 to extend laterally of the sleeve 7 and have pivoted thereto a head 11 carried by an operating handle 12. The operating handle 12 is provided with spaced plates 13 engaging opposite faces of the head 11 and the handle is also provided with a shaft 14 extending through an opening in the head whereby the handle is rotatably and pivotally connected to the polishing device. 65

The sleeve 7 is screw threaded to receive a locking nut 15 adapted to be turned home against the plate 8 for holding the latter to the outer element 3. The outer end of the sleeve 7 is closed by a removable cap 16 apertured to receive a stem 17 of a piston 18 slideable in a cylinder 19 which is slidably mounted in the sleeve 7 and projects beyond the inner end of the latter. The sleeve 7 and cylinder 19 are normally disposed vertically and the lower end of the cylinder 19 is closed by a removable cap 20 having a discharge opening 21. The cap 20 has detachably secured thereto a polish applying element 22, preferably constructed from fabric and is adapted to contact with the floor along with the brush portion 6 of the cocoanut covering or pod 5. The upper end of the cylinder 19 is closed except for an opening to permit sliding movement of the stem 17 of the piston and is engaged by a coil spring 23 bearing against the cap 16 for normally 70 urging the polish applying element 22 in engagement with the floor and causing the element 22 to readily follow unevenness that may be in the floor.

The outer end of the stem 17 is apertured to slidably receive a flexible element 24, one end of which is anchored to the cap 16 and the other end secured to the shaft 14 and wound thereon so that by rotating the handle, the piston 18 may be forced downwardly to expel a polishing medium through the cap 20 onto the floor. A pivoted 75 catch 25 is carried by the cap 16 and may be moved into engagement with a notch 26 in the stem 17 of the piston when desiring to lock the latter against movement.

The inner clamping element 2 is recessed to 100 receive a lock nut 27 threaded to the sleeve 7 and cooperating with the lock nut 15 in retaining the sleeve 7 assembled to the clamping elements 2 and 3.

While I have shown and described the preferred 105 embodiment of my invention, it will be understood that minor changes in construction, combination and arrangement of parts may be made without departing from the spirit and scope of my invention, as claimed.

Having described the invention, I claim:

1. A polishing device comprising inner and outer arcuate clamping elements, a cocoanut shell and its fibrous covering held by and between said elements, and a handle connected to the outer clamping element.
2. A polishing device comprising inner and outer arcuate clamping elements; a cocoanut shell in the fibrous coovering located between and held by said clamping elements, a handle connected to the outer element, and means including a member extending through the shell and the clamping elements to secure said shell and elements together.
3. A polishing device comprising inner and outer clamping elements, a cocoanut shell in the fibrous covering located between and held by said clamping elements, a handle pivotally and rotatably connected to the outer element, a polish reservoir carried by the inner and outer elements, means operable by rotation of said handle for feeding polishing material from said reservoir, and means carried by said reservoir for applying polish to a floor.
4. A polishing device comprising inner and outer clamping elements, a cocoanut shell in the fibrous covering located between and held by said clamping elements, a handle pivotally and rotatably connected to the outer element, a polish reservoir carried by the inner and outer elements, means operable by rotation of said handle for feeding polishing material from said reservoir, and means carried by said reservoir for applying pol-

ish to a floor, and tension means normally adjusting the polish applying means to a floor.

5. A polishing device comprising inner and outer clamping elements, a cocoanut shell in the fibrous covering located between and held by said clamping elements, a handle pivotally and rotatably connected to the outer element, a polish reservoir carried by the inner and outer elements, means operable by rotation of said handle for feeding polishing material from said reservoir, and means carried by said reservoir for applying polish to a floor, tension means normally adjusting the polish applying means to a floor, a piston for forcing polish out of said reservoir, and means between the handle and piston for causing actuation of the latter by the rotation of the handle.
6. A polishing device comprising inner and outer clamping elements, a cocoanut shell in the fibrous covering located between and held by said clamping elements, a handle pivotally and rotatably connected to the outer element, a polish reservoir carried by the inner and outer elements, means operable by rotation of said handle for feeding polishing material from said reservoir, and means carried by said reservoir for applying polish to a floor, tension means normally adjusting the polish applying means to a floor, a piston for forcing polish out of said reservoir, a flexible element having one end anchored to the reservoir and slidably engaging the piston and secured to and wound on the handle for effecting movement of the piston by rotation of the handle.
